US0D1107911S

(12) **United States Design Patent** (10) Patent No.: **US D1,107,911 S**
(45) Date of Patent: ** Dec. 30, 2025

(54) **ACETABULAR CUP REMOVAL DEVICE FOR ARTIFICIAL HIP JOINTS**

(71) Applicant: **IMEDICOM CO., LTD.**, Gunpo-Si (KR)

(72) Inventors: **Byoung Ju Lee**, Gunpo-si (KR); **Tae San Kim**, Gunpo-si (KR)

(**) Term: **15 Years**

(21) Appl. No.: **35/523,422**

(22) Filed: **Nov. 20, 2024**

(80) **Hague Agreement Data**

Int. Filing Date: **Nov. 20, 2024**

Int. Reg. No.: **DM/242894**

Int. Reg. Date: **Nov. 20, 2024**

Int. Reg. Pub. Date: **Dec. 27, 2024**

(30) **Foreign Application Priority Data**

May 30, 2024 (KR) 30-2024-0021178

(51) **LOC (15) Cl.** **24-02**

(52) **U.S. Cl.**

USPC **D24/133; D24/155**

(58) **Field of Classification Search**

USPC D24/155, 133, 135, 140, 143, 146, 147

CPC A61F 2/4603; A61F 2/4607; A61B 17/92

See application file for complete search history.

(57) **CLAIM**

The ornamental design for acetabular cup removal device for artificial hip joints as shown and described.

DESCRIPTION

1. Acetabular cup removal device for artificial hip joints

1.1 : Perspective

1.2 : Front

1.3 : Back

1.4 : Top

1.5 : Bottom

1.6 : Left

1.7 : Right

1 Claim, 7 Drawing Sheets
